DESIGN FOR A THERMOHYDROMETER

Arnold Z. Hoyer, Conshohocken, Pa., assignor to
Kimble Glass Company, Vineland, N. J., a cor-
poration of Illinois

Application November 17, 1944, Serial No. 116,399

Term of patent 14 years

(Cl. D52—7)

To all whom it may concern:

Be it known that I, Arnold Z. Hoyer, a citizen
of the United States, residing at Conshohocken,
in the county of Montgomery, State of Pennsyl-
vania, have invented a new, original, and orna-
mental Design for Thermohydrometer, of which
the following is a specification, reference being
had therein to the accompanying drawing, form-
ing a part thereof, in which

Fig. 1 is a front elevation of the thermohy-
drometer, embodying my new design; and
Fig. 2 is a side elevation of the thermohydrom-
eter shown in Fig. 1.

I claim:

The ornamental design for a thermohydrom-
eter, as shown.

ARNOLD Z. HOYER.
